United States Patent Office

Des. 185,688
Patented July 14, 1959

185,688

HEADLAMP DOOR

George W. Walker, Bloomfield Hills, Mich., assignor to Ford Motor Company, Dearborn, Mich., a corporation of Delaware

Application August 20, 1958, Serial No. 52,304

Term of patent 7 years

(Cl. D48—32)

Fig. 1 is a front elevational view of the headlamp door showing my new design;

Fig. 2 is a top plan view thereof;

Fig. 3 is a side elevational view thereof;

Fig. 4 is a sectional view taken substantially through the line 4—4 of Fig. 1 looking in the direction of the arrows; and

Fig. 5 is a sectional view taken substantially on the line 5—5 of the arrows.

I claim:

The ornamental design for a headlamp door, substantially as shown.
